UNITED STATES PATENT OFFICE.

ROBERT S. GRAHAM, OF ST. LOUIS, MISSOURI, ASSIGNOR OF ONE-HALF TO
ROBERT J. LUCAS, OF SAME PLACE.

DESIGN FOR A LOCK-PLATE FOR BOTTLE-STOPPERS.

SPECIFICATION forming part of Design No. 27,541, dated August 17, 1897.

Application filed January 30, 1897. Serial No. 621,363. Term of patent 14 years.

To all whom it may concern:

Be it known that I, ROBERT S. GRAHAM, a citizen of the United States, residing at the city of St. Louis, State of Missouri, have invented a new and original Design for Locks for Bottle-Stoppers, of which the following is a full, clear, and exact description, reference being had to the accompanying drawings, forming a part of this specification, wherein—

10 Figure 1 is a top plan view, and Fig. 2 is an edge view of the same.

The invention relates to an original design for lock-plates for bottle-stoppers; and it consists in a flat oblong plate or disk A, having 15 its opposite ends curved or rounded and its sides indented, as at a' in Figs. 1 and 2. The intersecting points are fashioned into

well-defined angles or points, as shown, from which points the walls of the indentations slope gradually toward the center of the plate. 20

The essential feature of the design is the flat plate having the curved ends, the indented sides with sloping walls, and the well-defined angular intersecting points.

What I claim is—

25 The design for a lock-plate for bottle-stoppers, substantially as shown and described.

In testimony whereof I hereunto affix my signature, in presence of two witnesses, this 25th day of January, 1897.

ROBERT S. GRAHAM.
